GEORGE B. REID, OF ABERDEEN, WASHINGTON

TRIGGER MECHANISM FOR FIREARMS

Application filed February 3, 1932. Serial No. 590,586.

My invention relates to trigger mechanism for firearms, and the general object of my invention is to provide a trigger mechanism in which the parts are arranged so that there will be no appreciable change in pressure of the trigger against the trigger finger at the instant the lock mechanism is released for firing.

In attaining accurate marksmanship with firearms, it is common practice to exert a gradual squeezing on the trigger. This obviates undesirable muscular reaction up to the instant of release of the trigger, but the usual trigger mechanism is constructed so that there is a very sharp and appreciable decrease in the resistance of the trigger to the finger at the instant of release of the lock mechanism. This release in the trigger pressure occurring at the time of firing is present in all firearms with which I am familiar. I have discovered that this release or "let-go" has an unfavorable reaction on the nerves and muscles of the person holding the firearm, and is very liable to result in movement of the firearm at the instant of discharge, thus resulting in inaccurate shooting and less perfect marksmanship than might otherwise be attained.

In accordance with my invention, I provide a trigger mechanism in which there is no appreciable release of trigger pressure against the finger at the instant the lock is released, thus overcoming, to a very large extent, the tendency to move the firearm off of the target at the instant of firing. I accomplish this by providing trigger mechanism embodying cam means arranged so that the pressure exerted by the lock mechanism against the trigger at the instant of release will be directed substantially toward the pin on which the trigger is pivoted.

With the usual trigger action the marksman must concentrate on two things, namely getting the gun aimed at the mark, and pulling the trigger while the gun is on the mark. With my device the marksman concentrates

only on the one thing of holding the gun on the mark, the pulling of the trigger being the result of squeezing, the marksman not knowing at exactly what instant the gun will go off and not experiencing any trigger reaction when it does go off.

The above mentioned general objects of my invention, together with others inherent in the same, are attained by the mechanism, illustrated in the following drawings, the same being preferred exemplary forms of embodiment of my invention, throughout which drawings like reference numerals indicate like parts:

Fig. 1 is an elevation of an automatic pistol which is equipped with a preferred form of trigger mechanism constructed in accordance with my invention.

Fig. 2 is a fragmentary view, partly in section, on a larger scale, of said trigger mechanism.

Fig. 3 is a detached perspective view of the mounting means for the trigger mechanism shown in Figs. 1 and 2.

Fig. 4 is a fragmentary view in elevation of a modified form of trigger mechanism in which an antifriction rolling contact is provided in connection with the trigger mechanism.

Fig. 5 is a fragmentary view in elevation, with parts in section, of a modified form of my invention in which a sear is provided between the trigger proper and the lock mechanism.

Fig. 6 is a fragmentary elevation of a modified form of the invention showing a roller mounted on the cam of the trigger.

Fig. 7 is a fragmentary view in elevation of another modified form similar to Fig. 5.

Fig. 8 is another fragmentary view in elevation of a modified form of my trigger mechanism showing the same applied to a bolt type gun lock.

Referring to Figs. 1 to 4 inclusive, I show an adaptation of my invention to an auto-

matic pistol. In these figures, 10 is an automatic pistol having a trigger guard 11 within which is the usual trigger 12, all of said parts being of well known standard construction. In accordance with my invention, I provide on said trigger 12, a cam contacting element which may be a lug 13 as shown in Figs. 1 and 2, or a roller 14 as shown in Fig. 4. An auxiliary trigger 15 having a cam 16 on its rear edge is fulcrumed on pivot pin 17 with the cam 16 in engagement with the cam contacting element 13 or 14. A bracket 18, shown partially broken away in Fig. 2, supports the auxiliary trigger 15, said bracket having spaced apart downwardly extending lugs 19 between which the trigger 15 is pivoted, and having two spaced apart side plates 20 which fit over the front portion of the trigger guard 11 and are adjustably secured to said trigger guard by a bolt 21 which extends through slots 22 in the side plates 20. The upper edges of the bracket 18 rest against the under side of the pistol so that the single bolt 21 is all that is required to hold the bracket 18 firm and immovable.

The lower portion of the cam 16 is preferably in the form of an even curve which breaks abruptly as at 23 and terminates in an inclined upper edge 24. A small compression spring 25, Fig. 2, disposed within a recess 26 in the bracket 18, presses against a shoulder 27 on the upper end of the trigger and serves always to bring the trigger back to the position of rest, shown in Figs. 1 and 4.

When the pistol is cocked, and the trigger is in the position of rest, as shown in Figs. 1 and 4, the cam contacting element 13 of Figure 1 or element 14 of Fig. 4 will rest against the trigger at, or just above, the location of the shoulder 23. When the auxiliary trigger 15 is pulled rearwardly, this cam contacting element will pass onto the curved cam portion 16, and the main trigger member 12 will be pressed rearwardly until the lock mechanism is released and the gun fired. The pressure of the cam contacting element 13 or 14 will always be directed substantially in a straight line against the pivot pin 17, and consequently there will be no appreciable release or release of pressure against the trigger finger at the instant of firing. The required pressure on the auxiliary trigger 15 will not vary appreciably as said trigger is pressed, and the marksman, as he squeezes the trigger, will not be able to foretell the exact instant of release of the lock mechanism. Neither will he be conscious of any release or variation in the pressure of the trigger against his finger at the instant of release of the lock.

In Fig. 5, I have shown my invention applied to a different form of gun lock. In this adaptation my trigger and cam and mounting are the same as in the preceding figures, but the usual trigger of the gun

is replaced by a sear 30 which is fulcrumed at 31. One end of the sear 30 engages a hammer 32, and the other end of such sear 30 engages with the trigger cam 16. The operation of this device is the same as described in connection with Figs. 1 to 4.

Fig. 6 discloses an adaptation of the invention similar to Fig. 4, except that an anti-friction roller 33 provided on the rear side of an auxiliary trigger 34 is adapted to press against a cam surface 35 on the main trigger 12 of a gun. In this adaptation, the roller 33 and cam surface 35 are relatively constructed and arranged so that the lock mechanism will be released at a time when the pressure of the main trigger 12 against the roller 33 is applied on a line which passes approximately through the pivot 17. For this reason, no appreciable release or "let-go" is experienced by the trigger finger at the instant of firing.

In Fig. 7, I show a modified form of the invention in which a cam 37 on a trigger 38 is operatively positioned in engagement with a sear 39. The trigger 38 is pivoted at 40. The relation of the pivot 40, cam 37 and sear 39 are such as to bring about release of the lock at substantially the instant when the pressure of the sear 39 against the cam 37 is directed squarely against the pivot pin 40. For this reason, no appreciable release is experienced by the trigger finger at the instant of firing.

In Fig. 8, I show an adaptation of my invention to a bolt type gun lock in which a bolt 41 is retained in cocked position by a catch member 42 which is pivoted at 43 and held in engagement with the bolt 41 by a spring 44. The usual trigger 45 pivoted in the catch member 42 has a pawl 46 engaging a relatively non-movable wall 47 whereby when the trigger is moved by exerting a pull or squeeze thereon the end of the catch member 42 will be moved downwardly and will release the bolt. In accordance with my invention, I mount an auxiliary trigger 48 on a pivot 49 in front of the trigger 45 and provide on said auxiliary trigger a cam member 50 disposed to engage the trigger 45. Obviously a pull on the auxiliary trigger 48 will move the trigger member 45 and release the bolt. The main trigger 45, cam 50 and pivot 49 are relatively positioned so as to release the bolt 41 at the instant the pressure of the main trigger member 45 on the cam 50 is directed substantially against the pivot 49. For this reason, no appreciable release is experienced by the trigger finger at the instant of firing.

In the adaptation shown in Fig. 8, the lower portion of the main trigger member 45, which has been indicated in broken lines, may be removed.

The mode of operation of the device embodying my invention is set forth in connec-

tion with the above description of the device. It is apparent that by arranging for the point of the cam, at which the release of the firing pin occurs to move substantially into the line joining the pivot point of the trigger 5 15, and the point 13 of the trigger 12 results in the reaction of the trigger mechanism to be assumed or taken up by the pin 17, rather than by the trigger finger. This delays the 10 15 recognition on the part of the marksman of the fact that the gun is discharged. In other words, he does not know during the time of firing that the gun is being discharged, so that there is no appreciation on his part of any 20 25 "let-go", the recognition of which results in an involuntary contraction of the muscles, so that the gun is moved off the line of aim before the discharge is completed. Such feeling of "let-go" results in a reaction of the nerves and muscles which tends to produce inaccurate marksmanship. Such reaction for 25 30 that moment is involuntary, and it is the mechanical elimination of this tendency that is one of the aims of my invention. The expert in the use of the firing arms as heretofore constructed manifests his ability in overcoming this involuntary reaction. By keeping the pressure relatively constant just before and just after the release of the firing mechanism and by directing the reaction of the 30 35 stresses of the trigger mechanism to the trigger pin of the trigger, avoids the recognition of the "let-go".

It will be manifest from the drawings and description that my invention may be readily added to guns already manufactured, by a slight alteration therein, or it may be built into the gun at the time of manufacture.

Obviously, other variations and adaptations of my invention may be devised in which the relation of the coacting parts is such that no appreciable release or "let-go" is experienced by the trigger finger at the instant of firing, and obviously, changes may be made in the forms, dimensions, and arrangement of the parts of my invention, without departing from the principle thereof, the above setting forth only preferred forms of embodiment.

50 I claim:

1. In auxiliary trigger mechanism for gun locks, a mounting member; means adjustably securing said mounting member to a trigger guard; an auxiliary trigger pivoted on said mounting member; and a cam on the rear edge of said auxiliary trigger.

2. In auxiliary trigger mechanism for gun locks, a mounting member having a bifurcated portion arranged to fit over a trigger guard bolt means adjustably securing said mounting member to said trigger guard; an auxiliary trigger pivoted on the rear end of said mounting member; and a cam on said auxiliary trigger for engagement with the hammer releasing mechanism of a gun lock.

3. In an auxiliary trigger mechanism for gun locks; a mounting member having a bifurcated forward end comprising two substantially parallel plates arranged to fit on opposite sides of a trigger guard, said plates having longitudinal slots therein; a bolt extending through said plates and through the trigger guard adjustably securing said mounting to said trigger guard; two downwardly projecting spaced apart lugs on the rear end of said mounting member; a trigger pivotally mounted between said lugs; a cam on the rear edge of said trigger; and a trigger spring interposed between said trigger and said mounting.

4. In a trigger mechanism, a pivotally mounted trigger; a releasing means, for a firing member, movable toward the pivotal mounting of said trigger; cam means operated by said trigger and disposed between said releasing means and said trigger; and means engaging the cam means with the releasing means and positioned at the instant of firing in the line of pressure of said releasing means towards said pivotal mounting of said trigger. 85 90

5. In a trigger mechanism, a pivotally mounted trigger; a releasing means, for a firing member, movable toward the pivotal mounting of said trigger; cam means rigid with said trigger and disposed between said releasing means and said trigger; and means engaging the cam means with the releasing means and positioned at the instant of firing in the line of pressure of said releasing means towards said pivotal mounting of said trigger.

6. In a trigger mechanism, a pivotally mounted trigger; releasable spring actuated firing means; devices holding said firing means in cocked position; a releasing means, for a firing member, movable toward the pivotal mounting of said trigger; cam means rigid with said trigger and disposed between said releasing means and said trigger; and means engaging the cam means with the releasing means and positioned at the instant of firing in the line of pressure of said releasing means towards said pivotal mounting of said trigger. 10 11 11

7. In a trigger mechanism, a pivotally mounted trigger; a releasing means, for a firing member, movable toward the pivotal mounting of said trigger; cam means operated by said trigger and disposed between said releasing means and said trigger; and roller means forming an anti-friction bearing engaging the cam means with the releasing means and positioned at the instant of firing in the line of pressure of said releasing means towards said pivotal mounting of said trigger. 120 125

8. In a trigger mechanism, a pivotally mounted auxiliary trigger means; a main trigger means operatively disposed as re- 130

as respects a firing member and movable toward the pivotal mounting of said auxiliary trigger means; cam means operated by said auxiliary trigger and disposed between said main trigger and said auxiliary trigger; and means engaging the cam means with said main trigger and positioned at the instant of firing in the line of pressure of said main trigger towards said pivotal mounting of said auxiliary trigger.

10 9. In a trigger mechanism, a pivotally mounted trigger; a firing member; sear means operatively disposed as respects said firing member and movable toward the pivotal mounting of said trigger; cam means operated by said trigger and disposed between said sear and said trigger; and means engaging the cam means with the sear means and positioned at the instant of firing in the line of pressure of said sear means towards said pivotal mounting of said trigger.

15 20 In witness whereof, I hereunto subscribe my name this 29th day of January, 1932.

GEORGE B. REID.
